APPARATUS FOR HOLDING GLASS PLATE DURING TEMPERING

Lewis Jex-Blake Forbes, St. Helens, England, assignor to The American Securit Company, Wilmington, Del., a company of Delaware

**Application June 3, 1935, Serial No. 24,729
In Great Britain June 8, 1934**

8 Claims. (Cl. 49—14)

This invention relates to the tempering of glass plates and has for its object an improved method and apparatus for holding the plates during the operations.

5 Heretofore, the methods employed have been
(1) to cut notches in the faces or edges of the
plates and engage the notches by suspended
hooks, (2) to grip the plate by its faces by tongs
having sharp points, and weight of the plate
10 tending to close the tongs to cause the points to
enter the glass, (3) to hold the plate in a three-
sided frame, provided with side clips to prevent
lateral movement of the plate in the frame.

The first of these methods has the disadvantage of requiring a preliminary operation for cutting the notches; the second has the disadvantage of making indentations in the faces of the plate which, for many purposes, are unsightly; the third method has the disadvantage that the frame with side clips protects portions of the plate from the tempering process.

According to the invention, the plate is held by its edges only in such a way that any pressure applied edgewise of the plate does not cause the plate to buckle when soft and in such a way that all parts of the plate are exposed to the tempering process.

Two members, having projecting points or knife-edges, are so located that their projections engage the two opposite side edges respectively of the plate, and pressure is applied to the members to cause them to grip the plate when cold and to cause their projections to enter the glass when heated sufficiently to become soft. Means are provided whereby the pressure between the projections and the glass is substantially released when the projections have entered the glass a predetermined distance, thus avoiding any pressure between the two edges of the glass sufficient to cause it to buckle when soft.

In the accompanying drawing:—

Figure 1 is a front elevation (with front plate removed) of a portion of one form of device according to the invention;

45 Figure 2 is a section thereof through the line A—A of Figure 1;

Figure 3 is a front elevation (with front plate removed) of another form, and

50 Figure 4 is a front elevation (partly broken away) of a third form.
Referring to Figures 1 and 2, the left top corner of the glass plate is shown at 1. On a supporting bar 2 there is adapted to slide a carriage composed of upper and lower bars 3 and 4 respectively to which are fixed plates 5, the front

side plate being removed in Figure 1. The carriage 3, 4, 5 can be secured to the bar 2 in any position by the screw 6. A lever with depending arm 7 and horizontal arm 8 is pivoted to a pin 9 fixed in the side plates 5. The arm 7 carries a projecting point or knife-edge 10, and the arm 8 carries a weight 11. The arm 8 is free to turn between an upper stop formed by the lower bar 4, at 12, and a lower stop 13. A similar carriage 3, 4, 5, with lever arms 7, 8, facing the other way, is on the bar 2 located so that its projection 10 is adapted to engage the right hand edge of the plate 1.

In operation, the two carriages 3, 4, 5, are slid towards one another, with the plate 1 between them, until the two projections 10 bear against the two edges of the plate, while the arms 8 are against their upper stops 12. The carriages are thus secured to the bar 2 by the screws 6. The weight 11 then maintains sufficient pressure of 20 on the projections 10 on the edges of the glass plate 1 to hold it.

When, in the process of tempering, the plate 1 is heated, it reaches a temperature at which the weights 11 are able to force the projections 10 into the glass, until the arms 8 bear against their lower stops 13. This occurs before the plate has become soft enough to buckle by the pressure on its edges, and the continued yielding of the glass releases the pressure down to a negligible amount 30 before the plate can be buckled.

Referring to Figure 3, which shows an alternative form of device, similar parts to those in Figures 1 and 2 are designated by the same reference numbers. A lever with arms 14 and 15 is pivoted on a pin 16 fixed in the side plates 5. The arm 14 carries the projecting point or knife-edge 10, and the arm 15 is forked so as to present two surfaces 17 and 18 to the stop 19. When the surface 17 is against the stop 19, as shown, the projection 10 is above the horizontal through the pivoting pin 16. As in the first described form, there is a similar device adapted to engage the right hand edge of the plate 1.

In operation, the carriages 3, 4, 5 are moved 45 until the projections 10 bear against opposite edges of the plate, while the surfaces 17 are against the stops 19. When the plate 1 is allowed to hang between the projections 10, the friction between them and the glass tends to turn 50 the arms 14 downwards, and this increases the pressure of the projections 10 on the glass.

When the plate softens sufficiently to allow the projections 10 to enter the glass, the arms 14 turn downwards until the surfaces 18 bear against 55

the stops 19. The pressure between the projections is then substantially released.

Referring to Figure 4, which shows another form of the invention, the plate 1 is supported in a frame consisting of a bottom bar 20 and side members 21. The bottom bar carries, at intervals, projecting points or knife-edges 22 on studs 23. The side members are composed of two bars 21, pivoted to the bar 20, one on each side of it, at 24. At their upper ends, the side members 21 carry pins 25 by which they are suspended from the supporting bar 2 by loops 26 and hooks 27. Also engaging the pins 25 is a cross bar 28, the pins 25 entering slots 29 in the bar. A rod 30, having a projecting point or knife-edge 10, is adapted to slide in a bush between the two bars of each side member 21 and to be secured therein by the screw 31.

In operation, the plate 1 is placed in the frame 20 so that its bottom edge rests on the projections 22. The rods 30 are then moved inwards, so that their projections 10 bear against the glass, while the pins 25 of the side members 21 are at the outer ends of the slots 29 in the cross bar 28. The rods 30 are then secured by the screws 31, and the hooks 27 are then suspended from the bar 2 in such positions that they tend to draw the pins 25 of the side members towards one another.

When the plate becomes soft, this pressure tending to draw the side members towards one another causes the projections 10 to enter the edges of the glass plate 1, until the pins 25 have reached the inner ends of the slots 29. The pressure is then taken by the cross bar 28, and is substantially released from the projections 10.

The plate 1 sinks by its weight on to the projections 22, as the projections 10 enter its edges, so that the indentations made by the projections 40 10 become slightly elongated. This elongation may be avoided, if desired, in various ways, as for instance, by so constructing the bushes through which the rods 30 pass that they can turn in the side members 21.

Having described my invention, I declare that what I claim and desire to secure by Letters Patent is:—

1. Apparatus for holding a plate of glass for tempering comprising two members having projections adapted to engage and enter the two opposite side edges respectively of the plate, means for applying pressure to the members to cause their projections to enter the glass when soft, and means for substantially releasing the pressure between the projections and the glass when the projections have entered the glass a predetermined distance.

2. Apparatus for holding a plate of glass for tempering comprising two supporting members 60 adjustable in respect of their distance apart, two members pivoted thereto respectively, having projections adapted to engage and enter the two opposite side edges respectively of the plate, means for applying pressure to the members to cause their projections to enter the glass when soft, and means for substantially releasing the pressure between the projections and the glass when the projections have entered the glass a predetermined distance.

3. Apparatus for holding a plate of glass for tempering comprising two supporting members 70 adjustable in respect of their distance apart, two members pivoted thereto respectively, having projections adapted to engage and enter the two opposite side edges respectively of the plate,

means for applying pressure to the members to cause their projections to enter the glass when soft, and a stop on each supporting member adapted to limit the movement of the pivoted member when its projection has entered the glass 5 a predetermined distance.

4. Apparatus for holding a plate of glass for tempering comprising two supporting members adjustable in respect of their distance apart, two members pivoted thereto respectively, having 10 projections adapted to engage and enter the two opposite side edges respectively of the plate, a weight attached to each pivoted member adapted to apply pressure to the member to cause its projection to enter the glass when soft, and means 15 for substantially releasing the pressure between the projections and the glass when the projections have entered the glass a predetermined distance.

5. Apparatus for holding a plate of glass for 20 tempering comprising two supporting members adjustable in respect of their distance apart, two members pivoted thereto respectively, having 25 projections adapted to engage and enter the two opposite side edges respectively of the plate, a weight attached to each pivoted member adapted to apply pressure to the member to cause its projection to enter the glass when soft, and a stop on each supporting member adapted to limit the movement of the pivoted member when its 30 projection has entered the glass a predetermined distance.

6. Apparatus for holding a plate of glass for tempering comprising two supporting members adjustable in respect of their distance apart, two members pivoted thereto respectively, having 35 projections adapted to engage and enter the two opposite side edges respectively of the plate, two stops on each supporting member adapted to limit the movement of the pivoted member so that 40 in the extreme position in one direction, the projection is above the horizontal through the pivot and in the extreme position in the other direction it is not below the said horizontal.

7. Apparatus for holding a plate of glass for 45 tempering, comprising a bottom member located below the plate, projections thereon adapted to engage the bottom edge of the plate, two side members pivoted thereto having projections 50 adapted to engage and enter the two opposite side edges respectively of the plate, means for applying pressure to the members to cause their projections to enter the glass when soft, and means for substantially releasing the pressure 55 between the projections and the glass when the projections have entered the glass a predetermined distance.

8. Apparatus for holding a plate of glass for tempering, comprising a bottom member located below the plate, projections thereon adapted to 60 engage the bottom edge of the plate, two side members pivoted thereto having projections adapted to engage and enter the two opposite side edges respectively of the plate, a supporting member above the plate, a suspending means 65 between each side member and the supporting bar, the points of attachment of the suspending means to the supporting bar being closer together than their points of attachment to the side members and means for substantially releasing 70 the pressure between the projections and the glass when the projections have entered the glass a predetermined distance.
